UNITED STATES PATENT OFFICE.

ALBERT E. LONG, OF PITTSBURGH, PENNSYLVANIA.

HOD:

Application filed December 18, 1922. Serial No. 607,679.

To all whom it may concern:

Be it known that I, ALBERT E. LONG, a citizen of the United States, residing at Pittsburgh, in the county of Allegheny and 5 State of Pennsylvania, have invented new and useful Improvements in Hods, of which the following is a specification.

This invention relates to hods, and more particularly to a hod intended for carrying 10 mortar and similar materials.

One of the main objects of the invention is to provide a hod of the character stated of simple construction and operation which may be readily produced and sold at coming 15 paratively small cost. A further object is to provide a hod which, when not in use, can be collapsed so as to occupy but little space and produce a compact bundle which can be readily carried on street cars and 20 similar public conveyances. Further objects will appear from the detailed description.

In the drawings:

Figure 1 is a side view of the hod;

Figure 2 is an end view;

25 Figures 3, 4 and 5 are sections taken substantially on lines 3—3, 4—4, and 5—5, respectively, of Figure 2;

Figure 6 is an end view of the hod in collapsed condition.

30 The hod includes a side board 1 to the lower edge of which is secured a side strip 2 disposed in angular relation to board 1. A sheet metal casing 3 extends about the lower portion of board 1 and about strip 2, 35 this casing projecting a slight distance above the upper edge of the strip. A second side board 4 fits on the upper edge of strip 2 and is braced against outward movement by casing 3 and by pins 5 carried by board 4 40 and fitting into recesses provided in the strip.

An end piece 6 is secured between board 1 and strip 2, at one end thereof, casing 3 extending about this end piece. Angle strips 45 7 are secured to the inner faces of boards 1 and 4 and are connected, adjacent to their lower ends, by a strip 7^a extending longitudinally of the upper edge of end piece 6. The outwardly projecting arms of strips 7 50 fit into corresponding grooves 8^a provided in the lateral edges of an end board 8 which fits between boards 1 and 4. End board 8 is also provided, in its lower end, with a groove 7^b which receives strip 7^a, the lower 55 end of board 8 fitting tightly against the upper end of end piece 6.

Eyes 9 are secured to boards 1 and 4 and receive the bills of hooks 10 which have their inner ends secured through eyes 11 of screw rods 12 slidable through angle brackets 13 secured to the outer face of end board 8. Rods 12 are oppositely threaded to receive a turnbuckle 12^a. A hook 14 is secured at its lower end, at 15, to end piece 6 and is adapted for engagement through eye 16 of a screw rod 17 threaded through one end of a turnbuckle 18 the other end of which is threaded onto a screw rod 19 secured by an eye 20 to an eye 21 secured to the end board 8 below brackets 13. By turning turnbuckle 12^a onto rods 12 the hooks 10 are drawn together so as to force the side boards tightly against the lateral edges of end board 8, and by turning turnbuckle 18 onto screw rods 17 and 19 the end board is 70 forced down into tight contact with end piece 6. This provides simple and efficient means for securing the end board and the side boards together in such manner as to effect a tight closure between the same, and 75 the angle strips 7 and strip 7^a effectually secure the end board against movement lengthwise of the hod while serving as bracing elements for the side boards.

80 Socket members 22 are secured to the outer faces of the side boards and are adapted for reception of the arms of a fork 23 which fits about the hod. A securing pawl 24 is pivoted on the outer face of board 4 adjacent to the upper end of socket member 22 and 85 is adapted to fit into a co-operating recess 25 cut in the adjacent arm of fork 23. This pawl is normally pressed toward the socket member by a spring 26. When the fork is inserted into the socket members pawl 24 90 engages into recess 25 and effectually locks the fork against casual displacement. The fork, when in position, serves to brace side board 4 against outward movement while 95 also providing simple and efficient means for lifting the hod. The lower end of fork 23 is secured in the upper end of a sleeve 27 the lower portion of which is interiorly threaded to receive the upper exteriorly threaded end portion of upper section 28^a of 100 a tubular standard or staff 28. Section 28^a is provided, at its lower end, with an interiorly threaded sleeve 29 for reception of the upper exteriorly threaded end portion of lower section 28^b of the staff. A block 105 30 is secured to and fits about the lower portion of the hod adjacent to fork 23, this 110

block being adapted to rest upon the hod carrier's shoulder.

When the hod is not in use it may be readily disassembled by loosening the turn-buckles 12^a and 18 and disengaging the hooks from their respective eyes, after which end board 8 may be readily removed from between the side boards. After this has been done the fork 23 can be removed by 10 moving pawl 24 into inoperative position and the side board 4 can then be detached from side strip 2. The staff may then be easily detached from the fork and the several sections of the staff can be dis- 15 connected, the fork together with the sec- tions of the staff and the end and side boards being placed in the hod between side board 1 and strip 2. When thus disassembled the hod may be readily arranged and packed so 20 as to occupy but very little space and pro- vide a compact bundle which can be readily carried in street cars and other public con- ve yances.

What I claim is:—

- 25 1. In a hod, a side board, a side strip se- cured to the lower edge of said board in angular relation thereto, a second side board seated on the upper edge of the strip, means for holding said second board against out- ward movement relative to the strip, an end piece secured between the first mentioned side board and said strip adjacent to one end thereof, an end board fitting between the side boards and seated upon the end 30 piece, means for forcing the side boards to- ward each other and for detachably secur- ing the end board to said side boards, and means for detachably securing the end board to the end piece and for forcing said end 35 board toward said end piece.
- 40 2. In a hod, a side board, a side strip se- cured to the lower edge of the board in an-

gular relation thereto, a second side board seating on the upper edge of said strip, an end piece secured between the first men- 45 tioned side board and the strip, a casing ex- tending about said first mentioned side board and the end piece and the strip, the casing projecting above the side strip and acting to brace the second mentioned side 50 board, an end board fitting between said side board and seated on the end piece, and means for detachably securing the end board to said side boards.

3. In a hod, a side board, a side strip se- 55 cured to the lower edge of the board in an- gular relation thereto, a second side board seated on the upper edge of said strip, an end piece secured between the strip and the first mentioned side board, an end board 60 between the side boards and seated on said strip, hook members carried by the end board, eyes carried by the side boards and positioned for reception of the hook mem- bers, means for adjusting the hook mem- 65 bers toward and away from each other, a hook member secured to the end piece, an eye member carried by the end board and adapted for reception of the hook member carried by the end piece, and means for ad- justing said eye member toward and away from said end piece.

4. In a hod, two side boards, means for 75 securing said boards together in angular re- lation, angle strips secured to the inner faces of the side boards, an end board fitting be- 80 tween the side boards and provided in its lateral edges with grooves receiving the inner flanges of said strips, and means for detachably securing said end board in po- sition.

In testimony whereof I affix my signa- ture.

ALBERT E. LONG.
